UNITED STATES PATENT OFFICE.

GEORGE B. NORRIS, OF COLUMBUS, OHIO, ASSIGNEE TO THE JEFFERSON MANUFACTURING COMPANY, OF COLUMBUS, OHIO, A CORPORATION OF OHIO.

MINING APPARATUS.

1,247,444.

Specification of Letters Patent.

Patented Nov. 20, 1917.

Application filed November 24, 1914, Serial No. 579,892. Renewed October 1, 1917. Serial No. 104,952.

To all whom it may concern:

Be it known that I, GEORGE B. NORRIS, a citizen of the United States, residing at Columbus, in the county of Franklin and State of Ohio, have invented certain new and useful Improvements in Mining Apparatus, of which the following is a specification, reference being had therein to the accompanying drawing.

10 The invention relates especially to a mining apparatus of the class in which the mining machine or cutting apparatus is or may be carried upon a wheeled truck and in which there is provided a reel, in this case separately mounted, for supplying current to the mining machine when it is in any one of a variety of positions with respect to the truck.

The principal object of the invention, therefore, is to provide in combination with a mining machine truck and a mining machine movably mounted thereon, a reel mounted separately from the mining machine on an independent wheeled truck and connected to the mining machine by means of a long flexible conductor which permits extended relative movements of the machine. Another object of the invention is to provide a reel-carrying truck of improved form. Still other objects will be apparent from the following specification.

Of the accompanying drawings, which illustrate the preferred embodiment of the invention,

Fig. 1 is a side elevation;

Fig. 2 is a plan view;

Fig. 3 is a side view of the cable reel truck;

Fig. 4 is a plan view of the cable reel truck;

Fig. 5 is a cross-sectional view through the cable reel mechanism;

Fig. 6 is a fragmentary end view of the cable reel mechanism;

Fig. 7 is a fragmentary side view of one of the current-collecting brushes;

Fig. 8 is a fragmentary perspective view, partly in section, and showing one of the bearings for the reel; and

Fig. 9 is a diagrammatic view showing the apparatus being moved into place in a room;

Fig. 10 is a view similar to Fig. 9, but showing the mining machine detached from the truck and cutting a kerf.

Referring to the drawings, A represents,

as a whole, the truck upon which the mining machine is supported. B represents the mining machine itself shown mounted on the truck but readily removable therefrom when it is to be operated. C represents the rotatable cable reel and the truck therefor connected to the mining machine truck A. D represents a flexible cable for connecting the reel and the cable thereon with the motor of the mining machine either when the mining machine is on the truck A or is separately supported, as shown in Fig. 10.

As concerns the details of the truck A there can be wide variation, but for purposes of illustration I have shown a truck having a main frame *a* formed with longitudinally arranged skids or rails for slidably supporting the mining machine. The frame is mounted on axles *b*, *b* and track wheels *c*, *c*, the two axles preferably being connected together by means of a chain *d*, passing over suitable sprocket wheels. Mounted upon the frame *a* is a power receiving element *e* which is here shown as a sprocket wheel. This power-receiving element is connected to the axles and the track wheels, a chain *f* passing over suitable sprocket wheels being here shown.

The mining machine B can be of any suitable form. For purposes of illustration I have shown a machine of the breast type, but it will be understood that the invention is not limited in this respect. The essential feature so far as certain phases of the invention are concerned is the mounting of the machine on the truck in such a way that it is movable with respect thereto and preferably entirely separable therefrom. I have shown a machine such as that presented in the patent to H. B. Dierdorff, No. 684,856, dated October 2, 1901.

The main or bed frame of the mining machine consists essentially of the side bars *g*, the cross bars *h* of suitable number, and the shoes *i* upon which the machine rests when in working positions. Within this frame is mounted the movable cutter frame, which is indicated in a general way by *k*. Around this cutter frame there travels an endless cutter chain *l*. At the rear the cutter frame is provided with a platform *m*, upon which is supported the electric motor *n*. The motor operates to drive the cutter chain and to move the cutter frame back-

- ward and forward relatively to the main frame in the usual manner, it being herein unnecessary either to show in detail the gearing for effecting these movements or to describe it at length. It should, however, be noted that this gearing comprises a transverse shaft *o* mounted on the movable cutter frame and provided at its ends with pinions *p* which mesh with the racks *q* secured to the main frame. Two sets of gearing are provided for connecting the shaft *a* with the motor, one set *r* serving to drive the shaft in one direction to feed the motor frame forward, and the other set *r'* serving to drive the shaft in the opposite direction to move the cutter frame backward. By means of a clutch *s* the shaft *o* can be connected with either set of gearing or can be entirely disconnected from both.
- 20 Mounted upon the mining machine and connected with the motor thereof so as to be rotated is a sprocket wheel *t* which is in alignment longitudinally with the sprocket wheel *e* on the truck frame; a chain *u* is provided which can be placed over these two sprocket wheels to connect them for the transmission of power when the mining machine is in place on the truck. When the mining machine is to be removed from the truck the chain is taken off.
- 25 The cable reel mechanism C comprises a truck 1 which consists of the wheels 2, axles 3, 3, and frame 4 mounted on the wheels in the usual manner. I have shown the truck as having four wheels, but it will be understood that the invention is not limited as concerns the number of wheels. The reel 5 is rigidly mounted upon the shaft 6 which is journaled in the bearings 7 and 8, supported by standards 9 and 10, respectively. These standards are bolted to the truck frame and in this manner the reel is supported with its axis horizontally arranged and transversely of the machine.
- 30 The bearing 7 is movable vertically in the ways 11 formed in the standard 9, and this vertical movement is accomplished by means of the lever 12 which is pivoted at 13 to the side walls 14, 14 of the standard. This lever has a short arm extending from the fulcrum point at 13 in under the bearing 7, and a long arm extending in the opposite direction adapted to be grasped by the operator. This longer arm is guided between the two bars of the standard 14', and can be locked in a lower or upper position of adjustment by means of the pin 15' which engages with apertures in the bars of the standard.
- 35 The other bearing 8 is cylindriform with its axis perpendicular to and intersecting the axis of the shaft 6; and its cylindrical outer face is socketed within the correspondingly curved block or standard 10. In this manner the bearing 8 can accommodate

itself to the different positions assumed by the shaft when the bearing 7 is shifted vertically.

The friction wheel 15 is keyed upon the shaft 6 between the reel and the bearing 7 and engages the treads of both of the truck wheels 2. When the lever 12 is in its upper position, the other arm of the lever is lowered to such a point that the friction wheel 15 rests solidly upon the wheels 2, and the lever is disengaged from the end face of the bearing 7. When the lever is in its lower position, its short arm is supporting the bearing 7 and the shaft 6, and the friction wheel is elevated above and out of contact with the wheels 2.

The reel consists of the metallic end plates 16 and 17 and the wooden drum secured between the plates, the plates being of greater diameter than the drum, and consequently, 85 extending radially outward beyond the drum so as to provide lateral retaining walls for the cable 18. The end plate 16 is of a simple disk-like form with a central hub 19 keyed to the shaft 6. The other end plate 90 17 consists of the hub 20, the annular plate 21 disposed in a vertical plane relatively nearer the adjacent bearing 8 than is the hub 20, and the connecting walls 22, the end plate being dish-shaped in its central parts 95 with a surrounding circular flange.

The cable 18 is secured at its inner end by one or more clamps 23 to the drum exterior, and passes through the aperture 24 to the chamber within the drum, and there branches. One part 25 passing through the gas-tight packing box 26 in the wall 22 and is secured at its end to the collector ring 27 mounted upon the wooden insulating sleeve 28 which is rigidly mounted upon the shaft 6. The other branch 29 of the cable likewise passes through a packing box 30 in another part of the wall 22 and is secured at its inner end to a second collector ring 31 which is also mounted upon the sleeve 28. The sleeve 100 is held in position longitudinally by means of the ring 32 which is pinned to the shaft 6 between the sleeve 28 and the bearing 8, and is also held against rotation relatively to the shaft by teeth or other projections in 105 the inner edge of the ring 32.

The current collecting mechanism is located entirely within the gas-tight cylindrical chamber 33 which is bounded at one end by the dish-like part of the end plate 17, 110 and at the other end by the cylindrical shield 34 which is bolted at its inner end to the end plate 17, and at its outer end is flanged centrally and machined to fit a circular shoulder upon the bearing piece 8. 115 This gas-tight chamber is in part located within the end plane of the drum and in part projects beyond this end plane.

The bearing 8 is formed with two integral inward extending arms 35, 35, disposed 120

parallel to the axis of the shaft 6 and in the outer parts of the chamber 33. To the inner face of each of these arms is bolted an insulating block 36 to which in turn is secured a collector brush 37. These brushes are adapted to be spring pressed against the corresponding collector rings 27 and 31. The brushes while held against rotation are nevertheless vertically movable with the reel. Current is conducted from the brushes by means of the wires 38, each secured at one end in one of the binding posts 39 and passing out through the vertical wall 40 of the bearing piece 8. The wires are surrounded by packing boxes 40^a at the points where the wall is penetrated.

110 Current is conducted from the brushes by means of the wires 38, each secured at one end in one of the binding posts 39 and passing out through the vertical wall 40 of the bearing piece 8. The wires are surrounded by packing boxes 40^a at the points where the wall is penetrated.

115 The cable is prevented from chafing upon the sharp edges of the end of the truck frame by means of a roller 41 mounted in a horizontal transverse position.

120 If desired a crank 42 may be provided which can be placed on either end of the reel shaft 6. As shown in the drawings the ends of the shaft are squared to receive the 25 crank.

The truck 1 is flexibly connected with the truck A by means of the link 43 and preferably the arrangement is such that the truck 1 can be readily detached when desired.

125 By a reference to Fig. 9 the preferred manner of using the apparatus will be readily understood. With the mining machine in place on the truck and with the chain α connecting the motor with the truck wheels the power of the motor can be utilized to turn the truck wheels and propel the truck about the mine. The reel truck 1 is flexibly connected with the mining machine truck and is hauled, or pushed by it. When the apparatus is moving forward the reel can, if desired, be held in elevated position, and the cable permitted to unwind from the reel under its own tension. When the apparatus moves backward the friction wheel 15 is permitted to contact with the track wheels 2-2, and in this way power is transmitted to rotate the reel and cause the winding of the cable as the apparatus moves. During all of these movements of the apparatus power is being transmitted through the cable 18 and the cable B to the mining machine motor.

130 The apparatus herein shown is capable of use in either of several varying ways, at option, and according to circumstances. But, during the time of any of these various uses, the same relations are maintained between the reel and the cable on the truck and the motor, in whatever position the latter may be placed.

135 In one case (that just above described) the current supplied from the reel truck to the motor is utilized to bodily propel the mining mechanism and its wheeled support, and also propel, simultaneously, the reel

truck, itself. This is done when taking the entire apparatus from one room to another in the mine; and also done when moving the cutting mechanism up toward the coal face.

140 In other cases, as when making small cuts in an "entry," the cutter part of the mining apparatus can be moved without taking the motor and other parts off from the truck as the cutter frame, proper, can, when the clutches are rightly adjusted, be moved outward to make cuts such as aforesaid on lines directly in front of the truck. And in still other cases, as illustrated in Fig. 10, the cutting mechanism of the apparatus may be separated from the wheeled frame and taken to a suitable place on the mine floor and set in operation.

145 Under any of the three conditions the cable from the reel truck and the electric cable connections are matters of great advantage.

What I claim is:

1. The combination of a low truck having a frame with supports for a mining machine and having supporting wheels for the frame, a mining mechanism including an electric motor on the said truck, a second wheeled truck flexibly connected to the first truck at one end thereof, a rotatable cable reel mounted on the second truck, an electric conductor cable on the reel, and electric conductor means including an elongated flexible cable adapted for electrically connecting the cable on the reel with the motor of the mining machine on the first truck in any one of several positions.

2. The combination of a low truck having a frame with longitudinally arranged mining machine supports and having supporting wheels for the frame, a second wheeled truck flexibly connected to the first truck at one end thereof, a rotatable cable reel mounted on the second truck, means connected with the truck wheels for driving the reel, an electric conductor cable on the reel, and electric conductor means including an elongated flexible cable adapted for electrically connecting the cable on the reel with the motor of a mining machine either on the first truck or in any one of a variety of positions separate therefrom.

3. The combination of a low truck having a frame with supports for a mining mechanism and having supporting wheels for the frame, a mining mechanism mounted on the said frame, a power receiving element on the frame connected with the truck wheels, a mining mechanism including an electric motor adapted to be supported on the truck, means for transmitting power from the motor to said power receiving element for the truck wheels, a second wheeled truck flexibly connected to the first truck at one end thereof, a rotatable cable reel mounted on the second truck, an electric

- conductor cable on the reel, and electric conductor means including an elongated flexible cable adapted for electrically connecting the cable on the reel with the motor 5 of the mining machine on the first truck in any one of a variety of positions.
4. The combination of a wheeled truck, a mining mechanism comprising cutting devices and an electric driving motor therefor, the said mechanism as a unit being 10 movably supported on the truck, a second wheeled truck flexibly connected to the first truck at one end thereof, a rotatable cable reel mounted on the second truck, an electric 15 conductor cable on the reel, and electric conductor means including an elongated flexible cable for electrically connecting the electric motor of the mining mechanism with the cable on the reel when the mechanism is in any one of a variety of positions 20 with respect to the first truck.
5. The combination of a wheeled truck, a mining mechanism comprising cutting devices and an electric driving motor therefor, the said mechanism as a unit being 25 movably supported on the truck, a second wheeled truck flexibly connected to the first truck at one end thereof, a rotatable cable reel mounted on the second truck for relative 30 vertical movement, means connected with the truck wheels for driving the reel, an electric conductor cable on the reel, and electric conductor means including an elongated flexible cable for electrically connecting 35 the electric motor of the mining mechanism with the cable on the reel when the mechanism is in any one of a variety of positions with respect to the first truck.
6. The combination of a wheeled truck, a 40 mining mechanism comprising cutting devices and an electric driving motor therefor, the said mechanism as a unit being movably supported on the truck, a second wheeled truck flexibly connected to the first truck 45 at one end thereof, a rotatable cable reel mounted on the second truck for relative vertical movement, a friction wheel fixedly connected with the reel at one end thereof and engaging one of the truck wheels to 50 support and drive the reel, means for lifting the reel and friction wheel to disengage the latter from the truck wheel, an electric conductor cable on the reel, and electric conductor means including an elongated flexible 55 cable for electrically connecting the electric motor of the mining mechanism with the cable on the reel when the mechanism is in

any one of a variety of positions with respect to the first truck.

7. The combination of a wheeled truck, a 60 mining machine adapted to be supported on the truck but separable therefrom, the said machine having an electric driving motor, a second wheeled truck flexibly connected to the first truck at one end thereof, 65 a rotatable cable reel mounted on the second truck, an electric conductor cable on the reel, and electric conductor means including an elongated flexible cable for electrically connecting the electric motor of the mining 70 mechanism with the cable on the reel when the mechanism is in any one of a variety of positions with respect to the first truck.

8. The combination of a wheeled truck, a mining machine adapted to be supported on the truck but separable therefrom, the said machine having an electric driving motor, means for transmitting the power of the motor to drive the truck wheels when the machine is in normal position on the truck, a 75 second wheeled truck flexibly connected to the first truck at one end thereof, a rotatable cable reel mounted on the second truck, an electric conductor cable on the reel, and electric conductor means including an elongated flexible cable for electrically connecting the electric motor of the mining mechanism with the cable on the reel when the mechanism is in any one of a variety of positions with respect to the first truck. 80

9. In a mining apparatus, the combination of a wheeled truck, a mining mechanism supported on the truck and having an electric motor, power transmitting devices between the motor and the cutting mechanism, 85 power transmitting devices for causing the movement of the mining mechanism, a second wheeled truck connected to the first truck to be propelled thereby, a rotatable reel on the second truck, an electric conductor cable on the reel, and electric conductor means, including a cable, for electrically connecting the cable on the reel with the said electric motor either for actuating the cutters or for bodily moving the 95 entire cutting mechanism, substantially as set forth.

In testimony whereof, I affix my signature, in presence of two witnesses.
